UNITED STATES PATENT OFFICE.

HIRAM M. LINDSAY, OF CHICKASHA, OKLAHOMA.

COMBINED SHADE AND CURTAIN HOLDER.

Application filed April 24, 1923. Serial No. 634,241.

To all whom it may concern:

Be it known that I, HIRAM M. LINDSAY, a citizen of the United States, residing at Chickasha, in the county of Grady and 5 State of Oklahoma, have invented certain new and useful Improvements in Combined Shade and Curtain Holders, of which the following is a specification.

In carrying out the present invention, it 10 is my purpose to provide a combined shade and curtain holder, that is adapted to be carried by the upper end of the sash frame, whereby the curtain and shade is raised or lowered in the raising or lowering of said 15 sash.

A further purpose of the invention is the provision of such a shade and curtain holder, wherein the same may be readily extended for use upon windows of varying 20 widths.

A still further purpose is to provide a device, that is a substantial improvement over similar devices, with which I am now familiar, my invention being characterized 25 by its simplicity of construction, and inexpensiveness of manufacture.

The nature and advantages of the invention will be better understood when the following detailed description is read in connection with the accompanying drawings, 30 the invention residing in the construction, combination, and arrangement of parts as claimed.

In the drawings forming part of this application, like numerals of reference indicate similar parts in the several views, and wherein:

Figure 1 is a front elevation of my improved shade and curtain holder, applied.

Figure 2 is an enlarged side elevation, partly in elevation of one of the supporting brackets comprised in my invention.

Figure 3 is a detail cross section taken substantially upon the line 3—3 of Figure 1.

Figure 4 is a perspective of one of the sliding fingers, constituting a part of the said supporting brackets.

Figure 5 is a perspective of one of these bracket elements, and

Figure 6 is a fragmentary longitudinal cross section of an extensible rod, also forming a part of this invention.

With reference to the drawings, and particularly Figure 1, 5 designates a window frame, 6 the upper sliding sash and 7 the lower sliding sash. Adjacent the upper cor-

ners of the sash 6, there is secured through the medium of screws or the like 8, supporting brackets designated generally A, each of these brackets are of identical construction, and a description of one will suffice for both. Each of these brackets consist of a pair of flat like metallic strips 9 and 10 joined together, inwardly of their ends by a rivet 11, the inner ends of each of these strips being so bent as to provide arms 12, that terminate in feet 13, that have close engagement with the frame of the sash 6.

The top strip 9 is bent forwardly at 14, for spacing the front ends of the strips apart, and in position between these strips is a pair of metallic plates 14, the front ends of which are bent upwardly to provide spaced fingers 15 for purposes hereinafter described. The said plates 14 are provided with elongated slots 16, through which extends a bolt 16 carried by the bracket, this bolt being provided with a bolt 17, whereby when the same is released, the plates 14 may be drawn outwardly from the bracket for supporting the shade and curtain at a desirable point forwardly of the sash.

Positioned between the fingers 15 of the brackets A are the outer ends of flat like rods 18, the inner end of the same being extended into an elongated metallic tube 19, whereby these rods may be moved towards or away from each other, for purposes of adjustment.

The ends of these rods extend beyond the brackets A, and are equipped with sliding shade brackets 20, it being of course understood that the bracket upon one rod is provided with an opening for the reception of the usual pintle upon one end of a shade roller, while the opposite bracket is provided with a notch, for the reception of the usual flattened end of the rod constituting a part of said shade roller.

In conjunction with the elements just described, there is provided an extensible rod 21 that is positioned rearwardly of the rods 18, the ends of this rod 21 being bent forwardly at 22, and thence inwardly at 23, these inwardly bent ends adapted for receiving the free ends of the rods 18.

In view of the above description, it will at once be apparent that I have provided an extremely simplified form of shade and curtain hanger, wherein the same may be adjusted for use in conjunction with windows of varying widths, other advantages of this

device being readily apparent to those skilled in the art.

Although I have herein set forth the most preferred embodiment of the present invention with which I am now familiar, it is nevertheless to be understood that minor changes may be made therein, without departing from the spirit and scope of the invention as claimed.

10 Having thus described my invention, what I claim as new, and desire to secure by Letters-Patent, is:

A combined window shade and curtain pole holder comprising spaced metallic strips secured together at a point between the ends and provided beyond the point where they are secured with angularly disposed ex-

tremities adapted to be applied to a window frame, other strips located between the spaced portions of the first mentioned strip and provided with longitudinally disposed slots, the securing bolt passing through spaced portions of the first mentioned strip and passing through the slots, the last mentioned strips having vertically disposed parallel end portions which are spaced from each other, a curtain pole disposed in the space between the vertically disposed portion of the last mentioned strip, and shade roller hangers mounted upon the curtain pole.

20 In testimony whereof I affix my signature.

25 HIRAM M. LINDSAY.
